UNITED STATES PATENT OFFICE.

ALBERT SETZER, OF PROVIDENCE, RHODE ISLAND.

ELECTRIC STORAGE BATTERY.

Application filed January 17, 1922. Serial No. 529,920.

To all whom it may concern:

Be it known that I, ALBERT SETZER, a citizen of the United States, residing at Providence, county of Providence, State of Rhode Island, have invented certain new and useful Improvements in Electric Storage Batteries, of which the following is a specification.

My invention relates to electric storage-batteries and consists in an improved means 10 for sealing the covers thereof to prevent leakage at the openings through which the binding-posts project.

One object of the improvement is to provide means for effecting a leak-proof joint 15 between the cover and the projecting posts to prevent the escape of the acid or other fluid from the battery cell.

Another object of the improvement is to provide a sealed joint which may be readily 20 opened to allow the removal and replacement of the cover without damage thereto.

Another object of the improvement is to provide a sealing-device which may be adjusted and locked in position to prevent it 25 from becoming loose under vibration and jar.

Further objects of the improvement are set forth in the following specification which describes a preferred embodiment of the invention as illustrated in the accompanying 30 drawings. In the drawings:

Fig. 1 is a vertical sectional view of the upper portion of a battery-cell showing my improved sealing-means as applied to the 35 cover and binding-posts thereof;

Fig. 2, a plan view of the sealing-cap;

Fig. 3, a vertical sectional view of the same taken on the line 3—3 of Fig. 2;

Fig. 4, a plan view of the pillar-strap of 40 the battery showing the post thereon.

Fig. 5, a perspective view of the locking key for the cap;

Fig. 6, a perspective view of the sealing-cap washer; and

Fig. 7, a similar view of the packing gasket for the sealing-cap.

My improved sealing-device is adapted for use with practically all styles of storage-batteries and in Fig. 1 I have illustrated a 50 conventional type of battery-cell which is enclosed within the usual hard-rubber jar 5. Arranged in opposed relation within the jar 5 are the battery electrodes comprising the usual plates or grids 6 and 7 which are 55 united at the top to flat metal pieces 8, sometimes called pillar-straps. Projecting up-

wardly from the straps 8 are the cylindrical posts 10 which are employed for connecting the grids of a plurality of the cells in series and for binding them to the terminals of the 60 circuit in which the battery is to be used. The pillar-straps 8 are arranged in horizontal position slightly below the top of the jar 5 and serve as rests or seats for a cover 12 of hard-rubber or similar dielectric and 65 acid-proof material which fits down against the straps within the upper rim of the jar.

The cover 12 is preferably molded with relatively thin walls which are ribbed or recessed to provide the required strength and 70 stiffness. As herein illustrated the cover 12 is recessed at 15 along its sides and provided with marginal flanges 14, the edges of which abut the inner walls of the jar 5. In attaching the cover to the jar 5 a melted cement 75 or sealing-compound, such as pitch or the like, is poured into the recess 15 and allowed to harden to seal the joint between the cover and the walls of the jar. This method of sealing has also been quite generally employed for closing the joints between the cover and the posts 10 which project therethrough, but such a sealing-means has been found unsatisfactory when used for the post openings for the following reasons: 80 In the first place, the shock and vibration to which the battery is subjected under road use in automobiles is liable to crack or break the seal and allow escape of the liquid from the battery; and furthermore with such a method it is well nigh impossible to unseal the cover from the posts without breaking it.

The grids or plates of the battery frequently require inspection and repair and 95 consequently it is desirable to provide a seal which will permit convenient removal and replacement of the cover. With this purpose in view I have now devised a novel and improved means for sealing the joints 100 between the cover and the posts while providing for the convenient removal and replacement of the cover. My improvement also includes provision for adjustment of the sealing-means to insure a leak-proof 105 joint, and an arrangement for locking the sealing-means to prevent it from becoming loose. The method of accomplishing these objects is as follows:

As shown in Fig. 1 the cover 12 is provided with circular recesses 16 surrounding the posts 10 and adapted to receive the 110

sealing-means for the openings there-through. The recesses 16 are provided by forming frusto-conical cups or depressions 17 in the upper wall of the cover 12, the bottom walls of which are adapted to rest against the top of the pillar-straps 8 and formed with circular openings 18 for receiving the posts 10. Within the tapered sides of each cup 17 I place a gasket 20, preferably constructed from unvulcanized rubber or similar compressible material, and having the form of a ring made cylindrical in cross-section. The gasket-ring 20 is preferably of slightly less internal diameter than the outside diameter of the post 10 so that it will cling snugly thereto when stretched therearound, and its cross-sectional area is such as to require compression of the rubber to force it into the space surrounding the post at the bottom of the recess 16. Above the gasket 20 I place a relatively thin washer 21, preferably constructed of vulcanized rubber or like material, and adapted to slide freely on the post 10. Above the washer 21 is placed a screw-cap or ring-nut 22 having tapered sides corresponding to the inclined sides of the recess 16 and provided with a flange 23 on its upper edge. The post 10 is formed with a square screw-thread 24 and the cap or nut 22 has its bore correspondingly screw-threaded to fit the post. As shown in Figs. 2 and 3, the threads 25 in the bore of the cap 22 are mutilated or cut through with vertical slots to provide key-ways 26 for a locking pin or key 27 as illustrated in Fig. 5. The slots 26 are adapted to register with a single spline or key-way 28 cut through the threads 24 on the post 10, as shown more particularly in Fig. 4. The key 27 is preferably rectangular in cross-section and provided with a head 29 at one end to adapt it to be pried out from the slots with a screw-driver or other tool.

The method of assembling the battery-cell with my improved cover-sealing means is as follows: The grids or plates 6 and 7 are placed in the jar 5 resting on its bottom and standing in vertical position in alternate opposite relation, in accordance with the usual arrangement. The two pillar-straps 8 on the opposite sets of plates will thus be supported in alinement in horizontal position adjacent the opposite ends of the jar 5, and slightly below its upper edge, as shown in Fig. 1. The cover 12 is set in place across the top of the jar 5 with the posts 10 projecting through its openings 18 and the bottom walls of the depressions or cups 17 resting on top of the straps 8. The gasket-rings 20 are next slipped on over the posts 10 and crowded down into the space at the bottom of the recesses 16. The washers 21 are then placed on the posts 10 above the gaskets 20 and the caps or nuts 22 en-

gaged with the threads 24 and screwed down against the washers. The caps 22 are turned down on the threads to force the washers 21 against the gaskets 20 to compress the latter, thus crowding the gaskets snugly into the bottom of the recesses 16 to conform them to the space at the bottom thereof, while also causing them to be compressed against the posts 10. In this manner the gaskets 20 are caused to bind the cover 12 tightly against the rests or pillar-straps 8 while also sealing the joint where the posts 10 project through the openings 18.

After the gaskets 20 have been forced into place in the manner as above explained the caps or ring-nuts 22 are locked in position by inserting the keys through the appropriate slots 26 in the threads of the nut which have been brought into register with the fixed slots or splines 28 in the threads of the posts 10. The caps 22 are thus caused to hold the gaskets 20 under compression and, being locked against unscrewing, prevent any play or movement between the parts. After the cover has been secured against the pillar-straps and the joints around the posts 10 sealed in the manner as above described the rim of the cover may be sealed to the sides of the jar 5 by any suitable method as, for instance, pouring cement or sealing compound into the recess 15.

It will be observed from the foregoing description that my improvement provides a most effectual fastening-means for attaching the cover to the pillar-strap posts and for sealing the joints therebetween. The sealing-devices are locked in place to prevent accidental release under shock or strain, while at the same time being adjustable to compensate for loss of compression if required. When it becomes necessary to remove the cover for inspection or repair of the cell the caps 22 may be unscrewed by withdrawing their keys 27. In this way the removal of the cover is effected by simply breaking the seal around its edge and without danger of rupturing the cover itself. After repairs have been made the cover is readily replaced and the seal applied again in the manner as first explained.

It is to be noted that the caps or attaching-means which secure the cover of the cell against the pillar-straps are enclosed within the recesses of the cover so that they do not project to any considerable extent above the top of the cell. This construction leaves the binding-posts free from obstruction so that the wire-terminals may be readily attached thereto without interference with the other elements. Furthermore, the terminal collars or binding-rings may be set close down against the top of the cover so that there will be less strain on the binding-posts and also less liability of the connections.

working loose. The arrangement also makes for a more compact and solid structure with less liability of rupture or breakage of the battery connections.

5 It has been demonstrated in practice that my improved sealing-device provides an absolutely tight, leak-proof joint which is impervious to, and proof against disintegration under the action of, the acid in the cell and which cannot be ruptured or broken by the vibration, shock or jar incident to hard usage. Furthermore, the sealing-means may be easily applied to the cover of the battery-cell and conveniently released therefrom and used continuously during repeated opening and closing of the cell without impairing its efficiency.

20 Various modifications may be made in the structure and arrangement of the parts of the device without departing from the spirit or scope of the invention and, therefore, without limiting myself in this respect, I claim:

25 1. In a battery cell, the combination with the electrodes thereof having relatively broad flat connecting straps extending horizontally thereabove with terminal-posts projecting upwardly therefrom, of a cover overlying the straps with its bottom resting thereagainst, said cover provided with recesses on its top having central openings through which the posts on the straps project, compressible gaskets surrounding the posts within the recesses of the cover, means 30 adjustable on the posts to compress the gaskets within the recesses to seal the joints between the posts and cover, and means to positively lock said compression-means in

adjusted position to prevent release of the gaskets under the effect of shock and strain. 40

2. In a battery cell, the combination of plate-like electrodes connected at the top by relatively broad flat pillar-straps having terminal-posts projecting upwardly therefrom, a cover having a flat bottom resting against and supported by the straps and formed with tapered recesses on its top provided with central openings through which the posts project, compressible gaskets surrounding the posts within the recesses, inferiorly-threaded caps screwed down on the posts within the recesses to compress the gaskets to seal the joints between the posts and cover, and means to positively lock the caps from unscrewing on the posts under 50 the effect of strain and vibration.

3. In a battery cell, the combination of plate-like electrodes connected at the top by relatively broad flat pillar-straps having terminal-posts projecting upwardly therefrom, a cover having a flat bottom resting against and supported by the straps and formed with tapered recesses on its top provided with central openings through which the posts project, compressible gaskets surrounding the posts within the recesses, inferiorly-threaded caps screwed down on the posts within the recesses to compress the gaskets to seal the joints between the posts and cover, said posts and caps having axially extending slots cut through their threads, and a key engaging the slots in the post and cap to lock the cap from unscrewing. 60

In testimony whereof I affix my signature.
ALBERT SETZER.
